UNITED STATES PATENT OFFICE.

MARY E. FRANCISCO, (ADMINISTRATRIX OF THE ESTATE OF HENRY FRANCISCO,) OF LAKE MILLS, WISCONSIN.

IMPROVEMENT IN SLEIGH-KNEES.

Specification forming part of Letters Patent No. **56,334**, dated July 10, 1866.

To all whom it may concern:

Be it known that HENRY FRANCISCO, late of Lake Mills, Jefferson county, State of Wisconsin, did invent a new and Improved Sleigh-Knee; and MARY E. FRANCISCO, the administratrix of the estate of said FRANCISCO, deceased, hereby declares that the following is a full, clear, and exact description of said invention, reference being had to the accompanying drawings, making a part of this specification, in which—

Figure 1 is a side elevation of the improved sleigh-knee applied to the runner and a portion of the body of a sleigh. Fig. 2 is an end view of the same. Fig. 3 is a longitudinal section taken in a vertical plane through Fig. 1. Fig. 4 is a section taken in a plane at right angles to that of Fig. 3. Fig. 5 is a top view of the improved sleigh-knee.

Similar letters of reference indicate corresponding parts in the several figures.

This invention relates to a novel mode of constructing those portions of a sleigh which are interposed between the runners and the body of the sleigh, and commonly termed "sleigh knees" or standards.

It is very important to secure a firm and substantial connection of the runners of "bobsleighs" to the bodies of the sleighs, and at the same time to obtain the required cant or inclination of the runners. This cannot be done successfully or cheaply with wooden knees, as they require to be large and clumsy in order to afford the required strength and bearing which are necessary to sustain a heavily-loaded sleigh, and as everything which is below the body of a sleigh will tend to impede its passage through the snow, it is desirable to construct sleigh-knees of cast metal in such manner as to afford the greatest strength in the least amount of space.

To this end the nature of this invention consists in forming hollow cast-metal knees for sleighs with their ends terminating in elongated bracket supports or bearings adapted to receive the cross-bars and runners of a sleigh, and to serve, in conjunction with bolts, to connect these parts together rigidly and permanently, as will be hereinafter described.

To enable others skilled in the art to under-

stand the invention of HENRY FRANCISCO, I will describe its construction and operation.

In the accompanying drawings one of the improved sleigh-knees is represented applied to a portion of the runner A and cross-beam B of a sleigh. The plank C is a portion of the flooring or sleigh-guard. This will fully illustrate the method of using the knees and the necessity for constructing them of the peculiar shape represented.

The central portion, *a*, of the sleigh-knee may be made cylindrical, its ends flaring outward, so as to form a bracket-shaped bearing, *b*, and a corresponding shaped support, *c*.

The knee is made hollow for the purpose of admitting of a bolt, *C'*, through it, which bolt passes up through the runner A, cross-beam B, and guard-plank C, and ties the whole firmly together. This knee is also made hollow, for the purpose of affording lightness.

The edges of the hollow bearing-portion *b* and *c* are made at right angles to each other, for the purpose of receiving the runners and the beams of the sleigh-body, which parts are at right angles to each other. The upper and lower edges of the sleigh-knee are formed so as to receive said runners and beams and to allow them to rest firmly against the thickened ends *g g h h* of the portions *b c*, through which ends holes are formed to receive bolts *D D* and *E E*, for holding these ends in their places upon their respective beams, as shown in Fig. 3.

It will be seen by reference to Figs. 1, 3, and 4 that the flanges of the bracket-bearing *b* enter grooves in the cross-beam B, and that the flanges of the bearing *c* extend over the edges of the runner A, thus preventing snow or water from getting within the knee.

Another important feature of the improved knees is that they are formed so as to give the required cant to the runners, when applied to the sleigh, without the necessity of cutting away the wood of the sleigh-beams to fit the parts to the knees. This cant or inclination is shown in Figs. 2 and 4, and it is obtained by giving the peculiar angle to the upper bearing-surfaces or end of the bracket *b*.

One great advantage of constructing sleigh-knees of cast-iron, or, what is still more pref-

erable, of malleable cast-iron, is that they can be cast in molds and will consequently be of a certain determined size—*i. e.*, there will not be a variation in the size or configuration of any of the knees so produced. Then, again, each knee will be formed of a single piece of metal, requiring no manipulation or finishing after it leaves the mold.

Having thus described the invention of HENRY FRANCISCO, it is desired to claim as new and secure by Letters Patent—

A hollow cast-metal sleigh-knee which is constructed with bracket-bearings on its ends, having closed sides, adapted to receive the frame-work of a sleigh, substantially as herein described.

MARY E. FRANCISCO,
Administratrix of Henry Francisco.
